UNITED STATES PATENT OFFICE.

WILLIAM A. LINES, OF SPOKANE, WASHINGTON.

SWITCH-THROW.

1,106,657.

Specification of Letters Patent.

Patented Aug. 11, 1914.

Application filed June 7, 1913. Serial No. 772,403.

To all whom it may concern:

Be it known that I, WILLIAM A. LINES, a citizen of the United States, residing at Spokane, in the county of Spokane and State 5 of Washington, have invented a new and useful Switch-Throw, of which the following is a specification.

The device forming the subject matter of 10 this application, is a mechanism for throwing a switch from a passing car or other vehicle.

The invention aims to provide novel 15 mechanism for operatively connecting the switch points with the wheel engaging members.

Another object of the invention is to provide a novel means for housing and protecting certain movable parts of the structure.

20 It is within the scope of the invention to improve generally and to enhance the utility of, devices of that type to which the present invention appertains.

With the above and other objects in view 25 which will appear as the description proceeds, the invention resides in the combination and arrangement of parts and in the details of construction hereinafter described and claimed, it being understood that 30 changes in the precise embodiment of invention herein disclosed can be made within the scope of what is claimed without departing from the spirit of the invention.

In the drawing:—Figure 1 shows the invention in top plan, the cover of the casing being removed; Fig. 2 is an elevation showing the inner face of one rail; Fig. 3 is a sectional elevation showing one of the wheel engaging members and attendant parts; 40 Fig. 4 is an elevation showing the other wheel engaging member; and Fig. 5 is an elevation showing a modification in sundry details of the invention.

In the drawings, the main line rails are 45 denoted by the numerals 1 and 2, the numeral 3 indicating the siding rails.

The numeral 4 indicates the switch points. In practice, there may be one switch point or 50 two, two switch points being shown in the present instance.

Located between the rails 1 and 2 is a casing 5. In practice, the casing 5 is housed in by a suitable cover, but for the sake of clearness in illustration, the cover 55 has not been shown in the present drawings. Disposed transversely of the casing 5 and

loosely mounted therein is a connecting rod 6, united with the switch points 4, the connecting rod being mounted to move in openings 7 in the rails. Extended longitudinally of the track and disposed transversely of the connecting rod 6, are actuating members, preferably taking the form of rods 8 and 9, the rods 8 and 9 being held for right line sliding movement in guides 10. A bell crank lever 11 is fulcrumed as indicated at 12 to one side of the connecting rod 6, one end of the bell crank lever 11 being loosely connected as indicated at 14 with the rod 6, the other end of the bell crank lever 11 being pivoted as indicated at 54 to the rod 8. A bell crank lever 15 is provided, the same being fulcrumed as indicated at 17, upon the opposite side of the rod 6 from the bell crank lever 11. As shown at 16, one end 70 of the bell crank lever 15 is loosely connected with the rod 6, the other end of the bell crank lever 15 being pivoted as indicated at 55 to the rod 9.

The rod 8 is provided with a rack 18 meshing into a pinion 19, secured to a primary shaft 20 journaled in the rails 1 and 2. The rod 9 is provided with a similar rack, meshing into a pinion 21 secured to the shaft 20.

85 Located upon the outside of the rails 1 and 2 are casings 22 in which hollow, wheel engaging members are located, the free ends of the wheel engaging members being adapted to rise out of the casings. The 90 wheel engaging member of the rail 1 is denoted by the numeral 23 and is provided adjacent its bottom with an opening 24. The wheel engaging member 23 is pivotally mounted upon a secondary shaft 25, and secured to the secondary shaft 25, inside of the rail, is a segment 26 meshing into a gear wheel 27 secured to the shaft 20. Secured to the shaft 25 and located on the outside of the rail 1 is a ratchet wheel 28 adapted 100 to be engaged by a pawl 29. The pawl 29 is pivoted to the wheel engaging member 23. A spring 30 engages the pawl 29. The lower end of the wheel engaging member 23 is disposed within a cup 31, located adjacent 105 the rail 1, and in the cup is placed mercury or other liquid which will not freeze. The spring 30 is secured to the bottom of the cup 31 and extends into the opening 24. Owing to the fact that the wheel engaging member 110 23 is provided with the opening 24, the mercury or other substance in the cup 31

will enter within the wheel engaging member 23 and the ratchet wheel 28, the pawl 29 and the spring 30 will be immersed, wholly or in part, in the mercury in the cup 31 and thus the operation of the device will not be impeded due to an accumulation of ice upon the pawl 29 or upon the spring 30.

The wheel engaging member of the rail 2 is denoted by the numeral 32. The wheel engaging member 32 is pivotally mounted upon the shaft 20, and secured to the outer end of the shaft 20 is a ratchet wheel 33, adapted to be engaged by a pawl 34, secured pivotally to the wheel engaging member 32, the pawl 34 being controlled by a spring 35. The mercury cup 36 hereinbefore described, is provided, as clearly shown in Fig. 3.

Journalized for rotation in the rail 1 is a shaft 37, provided at its outer end with an eccentric element shown in the form of an arm 38 which is adapted to engage with the free end of the wheel receiving member 23. Secured to the inner end of the shaft 27 is an armature 39, located in the field of an electromagnet 40, the conductors of which are denoted by the numeral 41.

A shaft 42 is journalized for rotation in the rail 2, the shaft 42 carrying an eccentric element in the form of an arm 43, adapted to come into contact with the wheel engaging member 32. Secured to the inner end of the shaft 43 is an armature, of the sort hereinbefore described, the armature being located within the field of an electromagnet 44, the conductors of which are denoted by the numeral 45.

In practical operation, the conductors 45 and 41 are extended beneath the pavement to a point adjacent the sidewalk, and thence are carried upwardly and inwardly toward the center of the track, so as to be capable of connection with the circuit of a passing car. Any suitable means upon the car may be provided for energizing the magnets 44 and 40 separately.

Suppose that the magnet 40 which is located adjacent the rail 1 is energized. Then the magnet 40 will attract the armature 39, causing a rotation of the shaft 37, the arm 38 of which will engage the free end of the wheel engaging member 23 and elevate the free end of the same, the shaft 25 constituting a fulcrum for the wheel engaging member 23. While the free end of the wheel engaging member 23 is being elevated, the pawl 29 will not engage the ratchet wheel 28 to rotate the same.

Presupposing that the wheel engaging member 23 has been lifted at its free end, as shown in Fig. 2, the wheel of the passing car engages the wheel engaging member 32 and depresses the same. Then, the pawl 29, engaging the ratchet wheel 28, will rotate the ratchet wheel 28 and the shaft 25, the segment 26 meshing into the gear wheel 27

and imparting rotation to the shaft 20. When the shaft 20 is rotated, the pinion 19 will be rotated, moving the rod 8, and the rod 8 through the instrumentality of the bell crank lever 11, shifting the connecting rod 6 in the direction of the arrow A, and actuating the switch points 4, accordingly, in the direction of the arrow A.

The member 32 may be depressed without elevating the member 23 because the pawl 29 on the member 23 is out of engagement with the ratchet wheel 28 when the member 23 is depressed to the limit, the pawl being in engagement with the ratchet wheel only when the depression of the member 23 begins. That end of the spring 30 which bears upon the pawl tilts the pawl out of engagement with the ratchet wheel when the member 23 approaches the limit of the downward stroke. The foregoing explanation holds true with respect to the pawl 34 and attendant parts. There is manifest utility in providing the rods 8 and 9 in duplicate, although these rods operate together. In the first place, the structure will be operative, should either one of the rods 8 and 9 and coacting mechanism be broken. Further, owing to the fact that the two levers 15-11 are provided, together with their respective rods 9 and 8, each rod bears but approximately one-half of the strain, and the tendency of the rods 8 and 9 to bend transversely, during the operation of the respective levers is reduced accordingly. Suppose, however, that the electromagnet 44 has been energized. Then, the magnet 44 will attract the corresponding armature and cause a rotation of the shaft 42, the shaft 42, through the instrumentality of the arm 43, effecting a lifting of the free end of the wheel engaging member 32 which is located adjacent the rail 2. During this operation, the pawl 31 will not rotate the ratchet wheel 33. So soon, however, as the free end of the wheel engaging member is depressed by the wheel of a passing car, the pawl 34 will engage the ratchet wheel 33 and rotate the ratchet wheel 33 together with the shaft 20.

When the shaft 20 is rotated in the manner hereinbefore described, the pinion 21 will be actuated, the same sliding the rod 9 and effecting a swinging movement of the bell crank lever 15, the latter moving the connecting rod 6 in the direction of the arrow B, the switch points 4 being set accordingly.

From the foregoing it will be observed that the switch points may be moved in opposite directions, depending upon whether the electromagnet 44 or the electromagnet 40 is energized.

Since the pinions 19 and 21 upon the shaft 20, together with connected mechanisms are actuated simultaneously when but one of the wheel engaging members 32 or 23 is actuated, it is obvious that there must be a lost

motion between the pawls and ratchets, of which the pawl 34 and the ratchet 33 may be taken as typical. The lost motion above referred to, will be explained in connection 5 with the members 34 and 33 as shown in Fig. 3.

When the free end of the wheel engaging member 32 is elevated, the free end of the spring 35 rides downwardly along the 10 edge of the pawl 34 and swings the lower end of the pawl into engagement with the ratchet wheel 33. When the free end of the wheel engaging member 32 is depressed, the pawl 34, at first, is interlocked with the 15 ratchet wheel 33, and secures a rotation of the ratchet wheel. However, as the wheel engaging member 32 moves downwardly toward the limit of its stroke, the free, upper end of the spring 35 ultimately rides upwardly above the pivotal mounting of the 20 pawl 34, and thus the pawl 34 is swung out of engagement with the ratchet wheel 33. Therefore, it will be seen that the necessary lost motion is provided.

25 In Fig. 5, a slightly modified form of the invention is shown. Referring to Fig. 5, the actuating member 56 replaces the actuating members 8 or 9 as shown in Fig. 1. The actuating member 56 is a rod, one end of 30 which is pivoted to a lever 46, fulcrumed at its lower end as indicated at 47 upon a rod or the like, extended between the rails, the lever 46 being provided with a slot 48 receiving a transverse rod 49 which serves as a 35 support and as a guide for the lever 46 in its swinging movement. The arm 46 is provided with a slot 50, receiving a pin 51, disposed upon a crank arm 52, secured to a shaft 53, the shaft 53 exercising the same 40 function as the shaft 20. The structure above referred to merely replaces the rack 18 and the pinions 19 and 21, and its operation and its place in the structure will be understood readily when Fig. 5 is compared 45 with the other figures of the drawings.

Having thus described the invention, what is claimed is:

1. In a device of the class described, a 50 switch point; a wheel engaging member operatively connected with the switch point; movable means for disposing said member in wheel engaging position, and including an armature; and an electromagnet to which the armature is responsive, the electromagnet being permanently fixed with respect to the armature.

2. In a device of the class described, a 55 switch point; a wheel engaging member operatively connected with the switch point; a shaft supported for rotation adjacent the

wheel engaging member and provided with an eccentric element adapted to engage the wheel engaging member; an armature secured eccentrically to the shaft; and an electromagnet to which the armature is responsive. 65

3. In a device of the class described, a switch point; a shaft supported for rotation and operatively connected with the switch point; an actuating member mounted 70 to move with respect to the shaft; a wheel engaging member, mechanism for operatively connecting the wheel engaging member with the shaft; a cup in which said mechanism dips; and a liquid in the cup, the 75 liquid having a lower freezing point than the freezing point of water.

4. In a device of the class described, a switch point; a rail; a shaft disposed transversely of the rail and supported for rotation; a pivotally supported wheel engaging member; pawl and ratchet mechanism operatively connecting the wheel engaging member with the shaft; an actuating member; means for operatively connecting the 80 operating member with the shaft; a pivotally supported lever operatively connected with the actuating member; and a connection between the lever and the switch point.

5. In a device of the class described, a 85 switch point and a rail; a pair of actuating members movable longitudinally of the rail; a connecting element united with the switch point; levers uniting the connecting element with the actuating members; a shaft supported for rotation and disposed transversely of the rail; means for operatively connecting the shaft with the actuating members; pivotally supported wheel engaging elements; and lost motion connections 90 between the wheel engaging elements and the shaft. 100

6. In a device of the class described, a switch point; a primary shaft supported for rotation; a secondary shaft supported for 105 rotation; a wheel engaging element mounted upon each shaft; pawl and ratchet connections between the wheel engaging elements and the shafts; intermeshing pinions connecting the shafts; a member operatively 110 connected with the switch point; and separate connections operatively uniting said member with the primary shaft.

In testimony that I claim the foregoing as my own, I have hereto affixed my signature 115 in the presence of two witnesses.

WILLIAM A. LINES.
